OUTLET RECEPTACLE

Harvey Hubbell, Jr., Bridgeport, Conn.

Application June 26, 1930, Serial No. 463,888

6 Claims. (Cl. 173—330)

This invention relates to new and useful improvements in outlet receptacles.

An object of the invention is to provide an outlet receptacle including a body having a solid or integral back, the contacts being loaded into the receptacle from the front, thus doing away with paper insulators which absorb moisture and may become conductors.

Another object is to provide an outlet receptacle wherein the ends of ears of the contact straps lock into the front or cover of the receptacle whereby the contacts are held in place against being pulled out of place in the receptacle or being separated from the receptacle.

This construction also provides a more rigid support for the binding screw for connecting a lead.

Another object is to provide a receptacle including a rib separating or insulating the contacts of the receptacle from one another, the rib being provided with a lug acting to prevent the front or cover member being placed in any but the right position on the receptacle when used as a polarized receptacle.

Other objects and advantages will become apparent from a consideration of the following detailed description taken in connection with the accompanying drawing showing one embodiment of the invention. While the invention is shown and described in detail it is to be understood that changes may be made without departing from the spirit of the invention or the scope of the appended claims.

In the drawing:

Fig. 1 is a plan or front view of the improved receptacle complete;

Fig. 2 is a sectional view on the line 2—2 of Fig. 5;

Fig. 3 is a side elevational view of the complete receptacle;

Fig. 4 is a sectional view on the line 4—4 of Fig. 1;

Fig. 5 is a plan view of the body of the receptacle, the front being removed;

Fig. 6 is a sectional view on the line 6—6 of Fig. 1;

Fig. 7 is a bottom plan view of the front or cover member, and

Fig. 8 is a bottom plan view of a contact removed from the receptacle.

Referring in detail to the drawing, at 10 is shown the body of the receptacle which may be of porcelain, bakelite, or similar moulded fire-proof insulating material and which includes side walls 11 and an integral bottom or base 12.

The bottom or base 12 being of insulating material and being integral with the remainder of the body 10 there is no occasion for employing paper or other insulating media which will absorb moisture and in the course of time become 5 a conductor.

Body 10 is hollow as shown and midway between its ends is divided by a partition 13 whereby to provide compartments 14 and 15 each adapted to receive a contact indicated in its entirety as 17. Partition 13 extends above the face of the body and at one end includes a lug 18, the purpose of which will later appear.

A front or cover member 19 closes the receptacle after the contacts 17 have been inserted 15 into the compartments 14 and 15 of the receptacle. This front member 19 is provided with openings 20 to permit of the insertion of the contacts of a plug and further at its underside the front 19 is grooved as at 21 to receive the 20 extended portion of the partition 13 as best shown in Fig. 4 whereby to assist in securing and positioning the front on the body 10 and to further insulate or separate the compartments 14 and 15. Further the openings 20 may, as best 25 shown in Figs. 1 and 7, be of different sizes whereby to polarize the device.

Front or cover 19 includes raised portions 22 and 23 which cooperate with the body when the front is placed on the body and raised portion 23 30 is cut away at 24 to accommodate the lug 18 of the partition or rib 13. Since raised portion 22 will not accommodate this lug 18 it is impossible to fit the front onto the body except when the front is properly positioned end for end. 35 Such an arrangement is advantageous when the device is used as a polarized receptacle.

Each of the compartments 14 and 15 includes a tapered or inclined wall 25 and a tapered rib 26 arranged on a wall at right angles to the wall 25. One side edge 26' of the rib 26 inclines or tapers outwardly from the top of the rib toward the bottom thereof, the bottom of the tapered edge of the rib being closer to the wall 25 than is the top of the rib. These inclined surfaces 40 co-operate in securing the contacts 17 within the respective compartments as will later be described.

Contacts 17 each include a base or connection portion 27 which as best shown in Fig. 8 is substantially U-shaped and from which projects upwardly the spring contact arms 28 and 29 for cooperating with the projecting contact fingers of different types of plugs or caps. The arms of the U-shaped connecting portions 27 of the contacts 50 55

opposite to arms 29 carry straps 30 through which pass binding posts 31 and which include offset fingers 32 at opposite sides of the binding posts 31. It will be obvious that the straps 30 or fingers 32 are disposed against the outer wall of the body 10 when the contacts are assembled in the body.

To accommodate the connecting portion 27 adjacent the strap 30, the wall of the receptacle is slotted at 16 providing access to each of the compartments 14 and 15 whereby the contacts may be inserted from the front of the body prior to the application of the front or cover member 19. As the contacts are pushed into the respective compartments the end portion 33 of the base member 15 will engage the tapered edge 26' of the rib 26 and the portion 34 of said base member 27 will engage the inclined wall 25. Also strap 30 is pressed against the side wall 45 of the body. Thus as the contact goes downward in its compartment in the body it must be forced or sprung between these oppositely inclined surfaces and also against the side wall of the body, this wedging action preventing or assisting in preventing movement of the contacts out of place due to any strain placed upon a wire connected with the binding post 31, and also holding the contacts stationary in the compartments to prevent their rattling.

The size of the contacts relative to the compartments is such that with the contact in place as above described strap 30 will be positioned against the outer wall of the body closing the slot 16. Further, this strap projects above the upper surface of the body and front member 19 is slotted or provided with recesses as at 35 to receive the upper ends 46 of the straps 30 thus locking the straps in place. Due to this arrangement further means are provided for maintaining the contacts in place, any pull downwardly and outwardly on the binding posts 31 due to a strain on a wire connected thereto will be taken care of due to the interlocking relation between the upper end of the straps 30 and the front or cover member 19.

The receptacle is provided with mounting straps or ears 36 provided with enlarged openings 37 to receive screws for securing the receptacle to a wall outlet box as will be understood. To accommodate these straps 36, the upper surfaces of the end portions of the front piece 19 are provided with depressions 38 and the portions of the straps 50 36 are likewise depressed as at 39 whereby the ends of the straps fit into the depressions 38 and are held against turning therein.

A convenient means is provided for securing all of the parts together and to this end the body 55 10 and front 19 are provided with aligned openings 40 and 41 through which passes a screw 43 threaded into tapped openings in the depressed portions 39 of the straps 36. Screws 43 holding the depressed portions 39 of the straps within the 60 depressions 38 in the front member such straps are secured against turning movement relative to the receptacle and other member. The straps may also have tapped openings 42 to receive the securing screws for the usual finishing or face 65 plate not shown.

From the foregoing it will be seen that the present outlet receptacle does not include any material capable of becoming impregnated with water or of absorbing moisture and thus the likelihood of danger due to failure of insulation is removed. Front member 19 may be of bakelite or similar material which is a good insulator and additionally has a good appearance. Contacts 17 may readily be pushed into their places in the 70 compartments 14 and 15 and will be securely held 75

therein due to the frictional engagement with the inclined walls as previously described and further the contacts will be held against movement due partly to this frictional engagement and due partially to the interlocking relationship between the 5 front member and the forward edge of the strap member 30.

Having thus set forth the nature of my invention, what I claim is:

1. In an outlet receptacle, a hollow body, a partition dividing said body into compartments each adapted to receive a contact, said partition extending beyond the front face of said body, an offset at one end of the projecting portion of said partition, a front or cover for said body having 15 openings of different sizes for the entrance of contact blades, and said front or cover having a slot to receive the projecting portion of the partition and a space to receive said offset when the front is properly positioned on the body whereby 20 to prevent the front from being placed on the body in reversed position.

2. In an outlet receptacle, a hollow body open at its front side and having a slot in one side wall, a contact in said body having a portion extending through said slot, a tapering rib on one of the inner walls of the body, a portion of said contact adapted to engage and wedge against a tapered side of said rib as the contact is pushed into the receptacle to assist in holding the contact against movement in the receptacle, a strap on the portion of the contact extending through the slot in the wall of the receptacle, said strap disposed against the outer wall of the body and extending beyond the front face thereof, a front or cover for said receptacle adapted to be secured on the front of said body, and said front or cover having a slot to receive the extending end of the strap to prevent a pull on the strap from moving the contact out of place in the receptacle. 40

3. In an outlet receptacle, a hollow body open at one side and having a slot in a side wall, a contact adapted to be inserted into the hollow body, the inner wall of said body including spaced oppositely inclined portions, said contact including a portion adapted to be pushed and wedged between said oppositely inclined portions as the contact is pushed into the receptacle, and said contact also including a portion extending through said slot carrying a support for a binding screw to engage an outer surface of the body whereby the contact is resiliently held against movement in the receptacle. 45

4. In an outlet receptacle, a hollow body open at one side and having a slot in a side wall, a contact in said body and having a portion extending through said slot, a tapered surface on one of the inner walls of the body, a strap on the portion of the contact extending through the slot in the wall of the body, said contact having a portion to engage and wedge against said tapered surface as the contact is pushed into the body to assist in holding the contact in place in the body and to draw said strap into engagement with an exterior wall of the body, and a cover for closing 60 the open side of the body. 65

5. In an outlet receptacle, a hollow molded body open at its front side and having a slot in one side wall, a contact adapted to be inserted into said body and including a portion extending 70 through said slot and a support for a binding screw at the outer side of said slot connected to said portion, one of the inner walls of the body having a tapered surface extending in the same general direction as said slot and facing away 75

from it, and said contact including a portion to engage said tapered surface while said support engages an outer surface of the body as the contact is pushed into the body to wedge the contact between said surfaces.

6. In an outlet receptacle, a hollow body open at one side and having a slot in a side wall, a contact in said body and having a portion extending through said slot, a tapered surface on one of the 10 inner walls of the body, a strap on the portion of the contact extending through the slot in the wall of the body, said contact having a portion

to engage and wedge against said tapered surface as the contact is pushed into the body to assist in holding the contact in place in the body and to draw said strap into engagement with an exterior wall of the body, said strap including an 5 extension projecting beyond the front face of the body, a cover secured on the front face of the body, and said cover having a slot receiving the extension of the strap and preventing a pull on the strap moving the contact out of place in the 10 receptacle.
